UNITED STATES PATENT OFFICE.

EDWARD B. HESS, OF NEW YORK, N. Y., ASSIGNOR, BY MESNE ASSIGNMENTS, TO ROYAL TYPEWRITER COMPANY, INC., OF NEW YORK, N. Y., A CORPORATION OF NEW YORK.

TYPE-WRITING MACHINE.

1,165,170.

Specification of Letters Patent. Patented Dec. 21, 1915.

Application filed June 3, 1911. Serial No. 631,070.

To all whom it may concern:

Be it known that I, EDWARD B. Hess, a citizen of the United States of America, residing in the borough of Manhattan, city, 5 county, and State of New York, have invented a certain new and useful Improvement in Type-Writing Machines, of which the following is a specification.

In U. S. Letters Patent No. 950,326, granted to me Feb. 22, 1910, I have shown card 10 controlling devices analogous to those herein disclosed and upon which the present invention is an improvement.

In the accompanying drawing: Figure 1 is 15 a top plan: Fig. 2, an end view with the side plate of the carriage broken away: Fig. 3, a similar view: Fig. 4, a detail sectional view showing a card holder extending up in front of the platen: Fig. 5, a front elevation: Fig. 6, a front elevation of the card 20 holder detached: Fig. 7, a similar view showing a modification: Fig. 8, a detail front elevation of one side of the card holder showing a part that may be extended across the printing line and swung 25 or folded down. Fig. 9 is a plan view of what is shown in Fig. 8: Fig. 10 is a front elevation and Fig. 11, a side elevation of a form of ribbon vibrator that may advantageously be employed.

The drawings show only so much of the carriage of a front strike typewriting machine of the style known as the "Royal Standard" as is deemed necessary to illustrate this invention.

The platen 1 is mounted in the usual carriage end plates 2.

3 is the shift rail and 4 indicates the bearing balls interposed between the bottom rail of the carriage and the shift rail. Ordinary rear feed rolls 5 and front feed rolls 6 are indicated as well as the usual paper table 7 and a paper pan 8 extending down under the platen between the front and rear feed rolls. On the shift rail is mounted a sheet metal card holder, generally designated by 9, and shown as made in one piece. It comprises a foot 10 bolted to the shift rail and an upwardly and forwardly extending portion 11 and an upright portion 12 that is extended laterally on each side and is formed with laterally forwardly inclined wings 13. Since this card holder shifts vertically with the carriage, its relation to the platen is a constant one and its upper edge, which lies at the base of the

line of printing, is engraved with a scale 14 and is parallel with the axis of the platen so that it constitutes a straight edge by which a sheet or card in the machine may be 60 alined or adjusted and also the scale affords a means by which any point on the platen may be definitely brought to the printing point, as for the insertion of a letter. Centrally, it is cut away or notched at 15 to permit the passage of the type heads to the printing point. On each side of this notch, and suitably adjacent the printing point, is an upwardly extending trowel-shape part 16 that is concavo convex in the direction 70 of the length of the platen and curved in the direction of the circumference of the platen. These parts 16 extend across and above the line of print. In the central part of the plate forming this card holder 9, generally 75 below the recess 15, the plate may be cut away as indicated at 17. This does not detract from the strength, reduces its weight, gives it an ornamental appearance, and provides space for other parts, as for instance, 80 a ribbon vibrator. In rear of the card holder there is shown the usual platen scale 18 which, as is well known, is or may be adapted to be moved to and from the printing line. It will be found in practice, however, that with the scale bearing card holder 9 the use of the ordinary platen scale 18 is not essential, except for gaging 85 long lines or scattered impressions. Co-operating with the card holder 9 is an upper card or paper clamp that comprises a 90 rod 19 on which, at suitably spaced intervals, are disposed rotatable paper clamping rollers 20. At its ends this rod is mounted in the front ends of forwardly extending 95 arms 21 pivoted upon a transverse rod 22 extending between the side plates of the carriage. In front of the rod 22, a reaction spring 23 is applied to each arm 21 and has its lower end connected with the side plate 100 at such point that, in normal position, the spring tends to draw the rollers 20 against the surface of the platen and, when the arms 21 are swung upwardly and rearwardly until the spring 23 passes the center of rod 22, 105 the reaction of the spring will tend to throw the arms down rearwardly and so hold them, thereby removing the front portion 19, 20 to entirely inoperative position. The paper clamping rollers 20 have their forward edges 110 in a vertical line in rear of a parallel line touching the upper ends of the card hold-

ing part 16 and therefore the rollers 20 are a substantial distance in rear of the printing surface on the platen. The general purpose of this arrangement is that, as shown in Fig. 2, an inserted sheet, card or envelop 24 may be allowed to pass upwardly from the card holder in front of the clamping rollers 20. This is rendered possible by reason of the fact that the rearwardly 10 extending card or paper holding parts 16 act in connection with the front feed rolls 6 to hold the card or paper closely against the surface of the platen at the point of printing.

15 In Figs. 2, 3, and 5, the card holding parts or fingers 16 are shown as integral with the card holding scale plate 9. A modification of this arrangement is shown in Figs. 4, 6, 7, 8 and 9 which indicate that one or both of 20 the curved card holding fingers 16' may be pivotally or otherwise movably connected with the card holding plate. Thus in Figs. 6 and 9, the left hand one of the curved fingers 16 is pivoted upon a screw bolt 25 and surrounding it and under its head is a spring washer 26. The scale plate has an angularly disposed embossed surface 27 against which the bottom circular part of finger 16' bears. This gives to the finger, when swung down, 30 an oblique plane of movement that carries it away from the platen. It will be obvious that the card holding finger or device 16' may be collapsed by being swung laterally as indicated in Figs. 8 and 9 so as to be removed from in front of the platen to afford 35 full visibility of the printed matter. With the device 16 at the left of the printing point swung down away from the printing line, as shown in Fig. 8, there will then be left 40 the finger 16' at the right of the printing point extending across the line of print, as shown in Fig. 6, to hold a card or paper against the platen. This finger 16 being integral with the card holder 9 avoids all 45 rough edges or projecting parts to interfere with insertion of cards, etc., or their movements while being printed, and being at the right of the printing line in no way obstructs the view of the operator, the words 50 as they are printed being fully exposed for his examination. This arrangement of one fixed guide finger extending across the line of print at the right of the printing point and integral with the card holder, which is 55 provided with a scale, are the essential features and constitute the gist of this invention.

Fig. 7 shows both of the members 16' so movably or pivotally connected with the 60 card holding plate 9 as to be collapsed or removed from in front of the platen.

Figs. 10 to 11 show an improved form of ribbon vibrator. In general contour it is

similar to those in common use being provided with bent over lips 28 that usually embrace and slide up and down upon the standard of the ordinary type bar guide located in front of the printing point. The slots 29, 29, through which the ribbon is to be threaded are located and formed as usual. The upper edge of the ribbon vibrator at each side is curved rearwardly as indicated at 30, as is also the downward extending lip that forms part of the outer wall of each slot as indicated at 31. This conformation of the vibrator permits the ready insertion, or threading, of the ribbon thereinto. The card holding finger or fingers movable downwardly from the printing surface of the platen so as not to obscure the printing line or surface thereof, either with or without the scale plate, is not claimed herein but is on the contrary part of one or more earlier applications filed by me Sept. 19, 1912, Ser. No. 721,230 (Patent No. 1074093); April 11, 1911, Ser. No. 618282; and October 12, 1912, Ser. No. 710,353.

I claim:

1. A card holding device for a typewriting machine comprising a card holding plate 90 rigidly mounted on to a part of the machine stationary with respect to the transverse traverse of the platen and a guide finger integral therewith extending upwardly across the line of print and at the right of the 95 printing point, the upper free edge of the card holding plate being just below the line of print, provided with a scale and extending a short distance to the left of the printing point, whereby the characters as printed 100 are unobstructed and all the characters of each line fully exposed to view as the printing of each line progresses.

2. A card holding device for a typewriting machine comprising a card holding plate 105 rigidly mounted on to a part of the machine stationary with respect to the transverse traverse of the platen and a guide finger integral therewith extending upwardly across the line of print and at the right of 110 the printing point, the upper free edge of the card holding plate being just below the line of print, having an opening for the printing instrumentality to pass therethrough at the left of the guide finger and 115 having a scale at each side of said opening, whereby the characters as printed are unobstructed and all the characters of each line fully exposed to view as the printing of each line progresses.

In testimony whereof, I have hereunto subscribed my name.

EDWARD B. HESS.
